AIR COOLER

Richard Wenzl, Freiburg, Germany

Application April 22, 1935, Serial No. 17,707
In Germany April 26, 1934

6 Claims. (Cl. 257—244)

My invention relates to air coolers for effecting the lowering of temperature in rooms, public buildings, etc., in storage rooms, such as the cellars of breweries, rooms where perishable goods 5 are kept, in short, wherever a lowering of the temperature is desirable.

It is an object of my invention to provide a cooler by which the air in the room etc. is cooled to a low temperature by an efficient refrigerant, 10 such as brine, or a cooling gas, but in which, notwithstanding the fact that the temperature at the outer surfaces of its cooling elements must never be higher than 0°, frosting is kept within such limits as not to give trouble, without un- 15 economic power demand or oversizing of the cooler.

To this end, I provide, in an air cooler, a cooling unit with flat cooling elements therein. Each element has a pair of parallel flat walls and the elements are so arranged that they define air ducts by the outer surfaces of their parallel flat walls. Means are provided for circulating an efficient refrigerant through the cooling elements at such a temperature that the outer surfaces of the duct-defining walls are maintained below 0°, and a flow of air through the ducts is established at comparatively high velocity.

By suitably selecting the temperature of the refrigerant, and imparting a proportionately high velocity to the air—which velocity should be higher than 13 ft. per second—frosting is not prevented but kept within reasonable limits. At the same time, the air is cooled to a temperature below 0°.

The problem underlying the present invention is to cool air to such low temperatures by a cooler which is similar to the heat exchangers used for cooling air to temperatures not below 5° above zero.

The cooling elements of my cooler are flat cells with two parallel flat side walls, and the walls have plain outer surfaces, without ribs or other outwardly extending projections. Baffles are arranged within the elements between their walls, 45 for conducting the refrigerant through the elements in a zig-zag path. With such flat elements, or cells, and with a properly determined ratio of the refrigerant temperature and the velocity at which the air flows in the ducts between the elements, as described above, the efficiency of the cooler is increased, and its size is reduced, as compared with the existing cooling plants. A cooler according to my invention is simpler and cheaper than such plants.

The simplicity of the parts constituting the ele-

ments, and the ease with which they are manufactured, facilitate quantity production of standardized parts.

The elements, when combined into a cooling unit, present a very large cooling surface in a 5 comparatively small unit. The efficiency is very high, on account of the high circulating velocity of the refrigerant, and the high flow velocity of the air.

Frosting is not eliminated, as mentioned, but 10 the flat and uniform surfaces of the elements forming the air ducts and the uniform lowering of the temperature, do not favor the local thickening of the frost into lumps which clog the ducts, and defrosting of the elements is rapid and uniform. 15

By providing elements as described, it is possible to depart from the present system of centralization adopted for cooling plants which is un- 20 economic and inconvenient, and to provide local plants comprising any number of flat cooling elements combined into as many units as may be required, at any desired station.

It is another object of my invention to increase the mechanical efficiency at which the air is moved through the cooler. To this end, I provide streamlined portions at the sides of the elements which extend transversely to the flow of the air in the ducts. Such streamlined portions are preferably formed by folding the walls of the elements down upon each other at the sides, and connecting 30 them by welding.

It is still another object of my invention to reduce the resistance opposed to the flow of the air at the inlet and outlet of the ducts. To this end, I provide bars for holding the elements, and connect the elements to the bars by brackets which are preferably placed outside the flow of the in-streaming and out-streaming air. The bars themselves are preferably streamlined.

In the accompanying drawings, a cooler embodying my invention is illustrated more or less diagrammatically by way of example.

In the drawings:

Fig. 1 is a vertical section of a cooler whose flat cooling elements are equipped with welded-in 45 baffles.

Fig. 2 is a section on the line II—II in Fig. 1,

Fig. 3 is a section on the line III—III in Fig. 1,

Fig. 4 is a section on the line IV—IV in Fig. 1, 50 showing the streamlined lower side of an element on a larger scale,

Figs. 5 and 6 are sections similar to Fig. 4 but showing modified elements,

Fig. 7 is a vertical section, and Fig. 8 is an 55

elevation, of a modified element whose baffles are formed by inwardly projecting ribs.

Referring now to the drawings, and first to Figs. 1 to 3, the flat elements 1 are combined into a cooling unit which is housed in a casing 2, of sheet metal or the like. The end edges 10, and the side edges 11, of the elements 1 are spaced from the corresponding portions of the casing 2, and the elements are held at their upper and lower side edges 11 by bars 14 in suitable frames 19 and 20 at the bottom and top of the casing 2. The individual elements are connected to their bars 14 by brackets 21. In the example illustrated, two brackets 21 are secured to the upper, and two more brackets 21 are secured to the lower edge 11 of each element, as shown in Fig. 1, and placed out of the way of the instreaming and outstreaming air.

The bars 14 may be of plain rectangular cross section, as shown in Fig. 4, but are preferably streamlined, as shown in Fig. 5. Fig. 6 illustrates a bar 14' of channel section between whose flanges the element 1 is held.

Each element has a pair of parallel walls 8 and 9 which are folded down upon each other at the upper and lower sides of the element and preferably connected by welding, as shown for the lower side of an element in Figs. 4, 5, and 6. The ends 10 of the elements may be connected 30 in a similar manner, as shown in Fig. 3.

Baffles 13 are inserted between the walls 8 and 9 of each element, and alternately connected to, and spaced from, the sides of the element. The baffles 13 are preferably welded to the walls, as shown in Fig. 4. One side of the baffle, in the example illustrated, that side which bears against the wall 9, is connected to the wall by two welds 22 and 23 at the upper and lower face of the baffle 13, and a fillet 24 in a slot, or fillets in holes, 40 of the other wall 8, connect that wall to the corresponding side of the baffle. The fillets 24 are constructed as follows:

The baffles are first welded to the inner side of the wall 9 by means of the two welds 22 and 23 (Fig. 4). In the side wall 8 before the cell is assembled there are bored a number of holes at suitable places and then the two walls 8 and 9 are brought together and secured in such a way that the holes in the wall 8, which latter form the fillets 24, will each be provided in the middle of one of the baffles. Then the holes are filled up by electric welding to form each fillet 24 and thus the fillet will be welded to its baffle and to the material of the wall 8. The 55 outer surface of the fillet 24 while still red hot is hammered flat and eventually any surplus metal is ground off in order that the outer surface of the wall 8 shall be perfectly smooth. Thus in view of the manner in which this fillet 60 24 is formed it is quite evident that a tight connection is made and therefore no leaks in the wall 8 will occur.

Refrigerant is circulated through the elements and between the baffles 13 by means of an inflow header 4, and an outflow header 5. The inflow header 4 is connected to the upper portion of each element by pipes 6 with flanges 25, and to the lower portion of each element the outflow header is connected by pipes 7 with flanges 26, so that the refrigerant flows as indicated by the 70 arrows 17 in Fig. 1.

The casing 2 of the cooler unit is secured to a tubular base 27 by angle sections 28. The lower end of the base 27 opens into a suction pipe 29 in which an adjustable damper 30 is mounted 75

on a suitable shaft 31, and turned by means of a handle 32 on one of its projecting ends.

A fan chamber 33 is placed on top of the unit casing 2, and connected to the casing by angle sections 34. A duct 35 is inserted in the front end 5 wall of chamber 33, and a fan 3, rotated by a motor 36 on a suitable bracket 37, rotates in the duct 35 to draw air from suction pipe 29 (whose free sectional area is regulated by the damper 30) through the ducts between the elements 1, 10 and to discharge it through duct 35.

A spray pipe 15, with perforations 16, is placed across the lower portion of the fan chamber 33 for defrosting the elements 1 by water issuing from the perforations 16. 15

In operation, a low-temperatured refrigerant, for instance, brine, is circulated through the elements 1 and deflected by the baffles, so that it flows through the elements at a suitable velocity. The walls 8 and 9 of the elements 1 are cooled to 20 temperatures below 0° and a correspondingly low cooling of the air flowing in the ducts between the elements is effected. As mentioned, the flowing velocity of the air should be comparatively 25 high in order to prevent excessive frosting and clogging of the ducts. The flow of the air to, through, and from, the ducts between the elements 1, and out of the casing, is as free from obstructions as practicable, and those members 30 which necessarily obstruct the flow, are of such configuration that the obstruction is reduced to a minimum. Any backing, whirling and local frosting are avoided, since the flowing air nowhere strikes large flat faces. The bars 14 and 14', even if not streamlined, are very narrow, 35 and the brackets 21 are out of the way. By these means, the efficiency of the cooler is much increased, trouble is eliminated, and the power demand is reduced.

Referring now to Figs. 7 and 8, this element 40 has the two parallel flat walls 8 and 9 as described, and its upper and lower sides are supported, in the example illustrated, by bars 14' of channel section, as shown in Fig. 6, but obviously bars such as illustrated in Figs. 4 and 5, with or 45 without the brackets 21, might be provided instead.

The welded-in baffles 13 described with reference to Figs. 1 to 4 are replaced by depressed ribs 18 in the plates 8 and 9 which are pitched 50 at equal distance from each other, and project inwardly for half the depth of the element. By these means, as will appear from Fig. 8, each two mating ribs make up a baffle. The inner sides of the ribs may be connected by any suitable means such as welded spots 38. The baffles 18 are arranged like the baffles 13, and the flow from pipe 6 to pipe 7 is indicated by arrows 17, as in Fig. 1. 55

It will appear that the element illustrated in Figs. 7 and 8 is as easily manufactured on a quantity production basis as the elements previously described.

It is understood that I am not limited to welding as the process of connecting the plates 8 and 9 of the elements, the baffles 13 and the depressed ribs 18 but that the plates may be connected by riveting, soldering, or in any other suitable manner. 65

Any number of elements 1 may be combined into cooling units, as described, and any number of such units may be connected in parallel or in series as required for a desired performance. The casings of the individual units may be placed 70 75

against a wall, as shown in Fig. 3, like a cabinet.

I claim:

1. In an air cooler, a cooling unit, flat cooling elements each comprising a pair of parallel flat walls, arranged in said unit to define air ducts by the outer surfaces of their parallel flat walls, means for circulating a refrigerant through said cooling elements at such a temperature that the outer surfaces of said walls are maintained at 5 a temperature below zero, baffles within each element for conducting the refrigerant through the element in a zig-zag path, a pair of welds connecting the upper and lower edges at one side of each baffle to the adjacent element wall, a 10 fillet in the other element wall for connecting it to the other side of the baffle, and means for establishing a flow of air through said air ducts at comparatively high velocity.
2. In an air cooler, a cooling unit, flat cooling 20 elements each comprising a pair of parallel flat walls, arranged in said unit to define air ducts by the outer surfaces of their parallel flat walls, means for circulating a refrigerant through said cooling elements at such a temperature that the 25 outer surfaces of said walls are maintained at a temperature below zero, means for establishing a flow of air through said air ducts at comparatively high velocity, and bars extending through said unit for holding said elements.
3. In an air cooler, a cooling unit, flat cooling 30 elements each comprising a pair of parallel flat walls, arranged in said unit to define air ducts by the outer surfaces of their parallel flat walls, means for circulating a refrigerant through said cooling elements at such a temperature that the 35 outer surfaces of said walls are maintained at a temperature below zero, means for establishing a flow of air through said air ducts at comparatively high velocity, bars extending through said unit for holding said elements, and brackets on 40 said elements for engaging said bars.
4. In an air cooler, a cooling unit, flat cooling elements each comprising a pair of parallel flat walls, arranged in said unit to define air ducts by the outer surfaces of their parallel flat walls, means for circulating a refrigerant through said 5 cooling elements at such a temperature that the outer surfaces of said walls are maintained at a temperature below zero, means for establishing a flow of air through said air ducts at comparatively high velocity, bars extending through said 10 unit for holding said elements, and brackets on said elements for engaging said bars, said brackets being arranged at the outer regions of the flow of the air.
5. In an air cooler, a cooling unit, flat cooling 15 elements each comprising a pair of parallel flat walls, arranged in said unit to define air ducts by the outer surfaces of their parallel flat walls, means for circulating refrigerant through said cooling elements at such a temperature that the 20 outer surfaces of said walls are maintained at a temperature below zero, means for establishing a flow of air through said air ducts at comparatively high velocity, and bars of streamline section extending through said unit for holding said 25 elements.
6. In an air cooler, a cooling unit, flat cooling 30 elements each comprising a pair of parallel flat walls, arranged in said unit to define air ducts by the outer surfaces of their parallel flat walls, means for circulating a refrigerant through said cooling elements at such a temperature that the 35 outer surfaces of said walls are maintained at a temperature below zero, means for establishing a flow of air through said air ducts at comparatively high velocity, and bars of channel section extending through said unit for holding said elements.

RICHARD WENZL. 40
